CLAIM

The ornamental design for a drinking vessel with locking lid as shown and described.

DESCRIPTION

FIG. 1 is a perspective view of a first embodiment of our design.

FIG. 2 is a top view of the first embodiment.

FIG. 3 is a bottom view of the first embodiment.

FIG. 4 is a right side of the first embodiment.

FIG. 5 is a left side of the first embodiment.

FIG. 6 is a front view of the first embodiment.

FIG. 7 is a back view of the first embodiment.

FIG. 8 is a perspective view of a second embodiment of our design.

FIG. 9 is a top view of the second embodiment.

FIG. 10 is a bottom view of the second embodiment.

FIG. 11 is a right side of the second embodiment.

FIG. 12 is a left side of the second embodiment.

FIG. 13 is a front view of the second embodiment; and,

FIG. 14 is a back view of the second embodiment.

The portions of the drinking vessel with locking lid shown in broken line form no part of the claimed design.
